FOUNTAIN PEN

Anthony G. Rosa, Lyndhurst, N. J.

Application April 26, 1948, Serial No. 23,247

6 Claims. (Cl. 120—42.15)

1

This invention relates to fountain pens, and more especially to improvements in fountain pens of the type in which the writing fluid itself is produced in situ.

An object of this invention is to provide an improved fountain pen which will produce writing fluid immediately, not only within the writing fluid chamber thereof, but also at the pen point so that the fountain pen can be satisfactorily used immediately for its intended writing purpose, without the annoyance of first having water or other unsatisfactory writing fluid emerge.

Another object of this invention is to provide an improved fountain pen of the aforementioned type having a novel arrangement of parts for the quick and efficient formation of writing fluid of the desired characteristics.

A further object of my present invention is to provide an improved fountain pen which carries sufficient ink-forming material so that it has to be refilled only very infrequently and then by a simple and convenient method employing a special refill device.

Other objects of this invention will become apparent from the following detailed description taken in connection with the accompanying drawings, which form a part hereof and in which like characters designate corresponding parts throughout.

In the drawings:

Fig. 1 is a longitudinal sectional view of a preferred embodiment of my invention;

Fig. 2 is an elevation of the feed and applicator of Fig. 1;

Fig. 3 is a cross-section taken along the line 3—3 of Fig. 2;

Fig. 4 is a cross-section taken along the line 4—4 of Fig. 2;

Fig. 5 is an enlarged view of the plunger, support bushing and cylinder shown in Fig. 1;

Fig. 6 is a part cross-section and part elevation of the cylinder of Figs. 1 and 5;

Fig. 7 is a broken longitudinal section of the lower portion of the cylinder of Figs. 1, 5 and 6, modified; and

Fig. 8 is a view, partly in section and partly in elevation, showing the arrangement of certain parts during the ink paste filling and re-filling operations.

Referring to the drawings, 15 is the barrel of my fountain pen. At its upper end it is rigidly attached to support bushing 16 and at its lower end the barrel is attached to pen section 17. While other suitable means for attaching the barrel to 16 and 17 may be employed, I prefer to use the threaded means shown in Fig. 1.

A removable cap 18 is attached, preferably by the threaded means shown in Fig. 1, to the upper part of the bushing 16. Under cap 18 is an externally-threaded plug 19 which engages with

2

the internally-threaded cartridge plunger 20. Disposed around the lower portion of plunger 20 is an envelope or cylinder 21 the upper part of which is securely but removably attached to bushing 16 by means of tie ring 22. The lower part of cylinder 21 has a piston-like portion 23 provided with annular grooves 24 (see Fig. 6) and with an opening 25 (see Fig. 5). The chamber 25a serves as the ink paste container.

Disposed within opening 25 is the top part of applicator 26. The lower part of applicator 26 is rigidly but removably attached to pen feed 27, either by suitable pin means (not shown) or by reason of having the cooperating parts of the proper size.

Applicator 26 has a longitudinal internal channel 28 and annular grooves 29 (see Figs. 2 and 3). Operatively linking said channel and grooves are transverse conduits 30 (Fig. 3) terminating in port openings 31.

Channel 28 of the applicator and duct 32 of the feed are disposed so as to form a unitary duct, terminating at its lower end in opening or notch 33. A feed channel 34 having capillary grooves 35 (Fig. 4) is also provided, in the usual manner, as is also pen point 36. The writing fluid is formed in chamber 37, which acts also as the reservoir for the writing fluid.

The operation of my improved fountain pen will now be described. It is assumed that at the outset the arrangement of parts is as shown in Fig. 1.

Cap 18 is first unscrewed from bushing 16. Plug 19 will thereby be exposed to view and can be unscrewed. A container 38 (Fig. 8) having an externally-threaded neck portion and provided also with a screw cap (not shown) and containing ink paste is operatively attached to plunger 20 by the threaded means shown. The ink paste is squeezed out of the container and forced into the ink paste chamber 25a, which can conveniently be made of a size adequate to hold a supply of ink paste which will last for several months, and even for years. After the contents of container 38 have been emptied into the chamber 25a, the container is removed and replaced by plug 19.

The pen point may then be immersed into water and downward pressure is applied on the plug 19. This forces plunger 20 downward and the plunger causes cylinder 21, which is secured near its top by tie ring 22, and which is made of rubber or other suitable flexible material, to stretch downward. During this downward motion of the cylinder the air in chamber 37 is substantially removed therefrom. Also, ink paste enters annular grooves 29 and some ink paste enters water ports 31 from where some of the paste goes through conduits 30 into duct 28. If desired, instead of immersing the pen point in

water at the outset as above indicated, the pen point may be immersed in water at this point.

When the downward pressure on plug 19 is released the resiliency of the rubber or other flexible material from which cylinder 21 is made causes the cylinder to be raised rapidly. Chamber 37 is thereby substantially evacuated of air and consequently water immediately flows through aperture 33, up duct 32 and channel 28, and then via conduits 30, out of water ports 31 into ink forming chamber 37. The ink paste which was contained in grooves 29 is immediately diluted and writing fluid of the correct characteristics is formed. Because of the presence in channel 28 of some ink paste at the start of the upward motion of cylinder 21, writing fluid forms in the channel, and the pen can be used immediately for writing purposes. Feed channel 34 and capillaries 35 serve the functions they normally do in fountain pens and hence their operation need not be described here.

While the applicator shown in the accompanying drawings has three annular grooves my invention is not to be construed as being so limited as one or more than three grooves may be present in the applicator. The exact number of grooves to be used in any given case will depend in the main on the size of the ink-forming chamber, the size of the grooves, and the concentration of the ink paste, and can easily be determined in any given case.

The use of a flexible cylinder in combination with a rigid, movable plunger and tie ring is not restricted to an ink-forming fountain pen as herein described, but in modified form applies to the regular type of known fountain pens. Fig. 7 shows the construction of part of such a modified cylinder which could be so employed. It is noted that there is no opening (as in 25 of Fig. 5) herein.

As will be understood by those skilled in the art the purposes of this invention can be attained by the use of various materials. That is to say, this invention is not to be limited to the use of any particular material or materials of construction, unless otherwise specifically provided herein. Merely by way of illustration and not for purposes of limitation I may mention the following as preferred materials for the parts indicated: hard rubber or cellulose acetate for the barrel and cap; gold for the pen point; hard rubber for the feed and pen section; polymethacrylate (Lucite) for the applicator; rubber for the cylinder; brass for the cartridge plunger; and brass for the plug.

While this invention has been described in detail in order to enable those skilled in the art clearly to understand it, it will be understood that all modifications that do not depart from the spirit of this invention are intended to be secured herein if they come within the scope of the appended claims. Thus, while the invention has been described with special relation to the common type of fountain pens, it is not to be limited thereto, as it is also applicable to other fountain pen types such as ball point pens, as well as perfume dispensers, e. g., of the ball point type.

I claim:

1. A fountain pen suitable for the rapid production of writing fluid in situ, which comprises the combination of a pen barrel, a hollow plunger movable within said barrel, a resilient cylinder-like member having its rear end fixed to said barrel and having a small central opening at its anterior end and being longitudinally stretchable

over said plunger, a tube-like applicator closed at one end, which end snugly fits into said central opening, said applicator having at least one annular circumferential groove for retaining ink paste, said barrel having therein an ink-forming and -retaining reservoir anterior of said cylinder-like member, and a pen feed engaging the lower part of said applicator, said feed and said applicator having a conduit therein.

2. The combination of claim 1, wherein one opening of said conduit terminates at said annular grooves.

3. A fountain pen suitable for the rapid production of writing fluid in situ, which comprises the combination of a pen barrel, a hollow plunger movable within said barrel, a flexible cylinder operatively engaging with said plunger and longitudinally stretchable thereover, said cylinder having its rear end fixed to said barrel and having annular recesses at its anterior end and a small central opening therein, a tube-like applicator closed at one end, which end snugly fits into said central opening, said applicator having a plurality annular circumferential grooves for retaining ink paste, said barrel having therein an ink-forming and -retaining reservoir anterior of said cylinder-like member, and a pen feed engaging the lower part of said applicator, said feed and said applicator having a conduit extending therethrough and having an opening into said reservoir.

4. The combination of claim 3, wherein the top of the conduit terminates at said annular grooves.

5. The combination in a two-chambered fountain pen suitable for the rapid production of writing fluid in situ, which comprises a piston septum between the chambers, said septum having a small central opening therein, a tube-like applicator closed at one end, which end snugly fits into said central opening, said applicator having at least one annular groove therein, and a pen feed having a longitudinal circumferential channel and operatively engaging the lower part of said applicator, said feed and said applicator having a conduit extending interiorly through part of said applicator and part of said feed, said conduit having one opening in said channel of said feed and another opening externally of the applicator.

6. The combination of claim 5, in which the other opening of the conduit is in said annular grooves.

ANTHONY G. ROSA.
